United States Patent

Des. 239,983
Patented May 25, 1976

239,983

SPORTS SHOE

Jonas Senter, Greenwich, Conn., assignor to CITC Industries, New York, N.Y.

Filed Sept. 11, 1974, Ser. No. 505,200

Term of patent 14 years

Int. Cl. D2—04

U.S. Cl. D2—310

FIG. 1

FIG. 2

FIG. 3

FIG. 4

FIG. 5

FIG. 1 is a front and side perspective view of a sports shoe showing my new design;

FIG. 2 is a front elevational view thereof;

FIG. 3 is an opposite side elevational view thereof;

FIG. 4 is a top plan view thereof; and

FIG. 5 is a rear elevational view thereof.

I claim:

The ornamental design for a sports shoe, as shown.
